UNITED STATES PATENT OFFICE.

JOSEPH HUTCHISON, OF GLASGOW, COUNTY OF LANARK, SCOTLAND.

TYPE-WRITING MACHINE.

SPECIFICATION forming part of Letters Patent No. 425,799, dated April 15, 1890.

Application filed March 19, 1889. Serial No. 303,902. (No model.) Patented in England February 11, 1888, No. 2,100.

To all whom it may concern:

Be it known that I, JOSEPH HUTCHISON, residing in Glasgow, in the county of Lanark, Scotland, a subject of the Queen of Great Britain and Ireland, have invented Improvements in Type-Writing or Printing Machines, (for which I have obtained a British patent, No. 2,100, dated February 11, 1888,) of which the following is a specification.

This invention has reference to and comprises certain improvements applicable to type-writers such as the "Remington," the "Hammond," and others, which improvements are susceptible of slight modifications to make them suitable for the different classes of machines, and will make these more comprehensive and quicker in producing the work and more automatic in their action than they have been as heretofore constructed.

Stated generally, the first improvement relates to the use of certain keys and levers, with two, three, or more letters in the longitudinal direction on the point of each of the levers in place of one letter in this direction, as heretofore, and which letters are frequently repeated in writing—such as "th," "is," "it," "er," "at," "to," "as," "on," "in," for double letters, and "the," "for," and "day" for treble letters, and in so fitting the bar and levers which these keys move to cause the rack mechanism and its pawl by certain improvements to move the paper carriage two, three, or more teeth forward in the longitudinal direction, according to the lever and number of letters brought into action at the time—that is, two teeth for two letters and three teeth for three letters, and so on, in place of one tooth for one letter only, as heretofore practiced, and still allow the single-letter keys and their levers to take the carriage forward one tooth of the rack for each single letter in the same manner as formerly.

In the accompanying drawings, Figure 1 is a longitudinal rear elevation, partly in section. Fig. 2 is a corresponding plan of the same, and Fig. 3 is a transverse sectional elevation corresponding to and as taken near the irregular lines 1 1 and 2 2 on Fig. 1, all of a type-writing or printing machine of the Remington class as fitted with my improvements. Figs. 4 to 8 show detail views of the improved parts, which will hereinafter be more particu-

larly described and referred to. Figs. 1^A, 2^A, and 3^A are separate views of the devices for operating the feed-roll. Fig. 4^A is a view 55 similar to Fig. 3, but drawn to a larger scale, and for the sake of clearness omitting parts not essential to this present invention; and Figs. 5^A and 6^A are views of a modification.

Referring to the drawings, 1 represents the 60 lower base fixed frame of the machine; 1', the upper fixed frame secured to the lower base frame by the four standards 1'', and which combined frame carries the mechanism of the whole machine portably in the usual manner, generally on four rubber feet z, resting in recesses in a plain wood frame or table z', to which a light tin or cased box cover is usually attached inclosing and protecting the whole machine when not in use. The finger-levers 2, with the alphabetical buttons 2' on their front free ends, are mounted to swivel by a groove on a rounded edge rib 3, projecting down from the lower frame 1 at the back, with light springs 3' over the back for raising the levers 2 up against a soft rest 3'' in front. These levers are arranged like piano-keys, stepped downward in the front open part of the lower frame 1, and have small studs or pins 2'' projecting down between 80 them to keep them separate. Each lever 2 would be fitted with a link 4 above near the center, connected by a light adjustable screw wire rod 4', linked at top to the short horizontal arm 5' of the type-lever 5, fulcrumed 85 to small brackets 5'', screwed to a ring-frame carried on the main top frame 1', as seen in Fig. 2, so that each type-lever arm 5, with the type 6 on it, strikes under an inking-ribbon r in the center of the ring-frame, so as to print 90 the letters on the under periphery of the paper-roller 7, which would have the paper passed under it, as indicated by the arrows and dotted lines p, and carried on the lateral moving case 8' on and within the usual longitudinal traversing open frame 8, running by pulleys 9' and 10' on the back and front guide-bars 9 and 10, all constructed as so far described in a usual manner. A flat band 11, passing over a segmental pulley 11', having its other end 95 attached to the frame 8 at 11'', pulls the frame 8 by a coiled spring fitted and wound up within the segmental pulley 11' always in one direction, as indicated by the arrow on

the frame A, over the lateral reciprocating ratchet-toothed divided or spacing bar 12, carried and reciprocated on two levers 13 up through and over the back end of the top frame 1'. These levers 13 are secured by adjusting pinching-screws on a longitudinal spring-spindle 14, oscillated in bearings under the back of the top frame 1' by two long U-shaped arm-levers 15, having the top 5 of their front arms connected by links 16 to a cross-bar 17, fitted under the whole of the levers 2, so that any one lever by depressing this bar 17 oscillates these two levers 15 and 13, and also the spacing toothed rack 12, fixed 10 on the upper end of the latter. This bar 17 is also actuated by the two end levers 2' of the set of levers 2, connected by a front longitudinal finger-bar at 1^x at the extreme front 15 of the lower frame 1, clear of all the finger-buttons 2', so that by depressing this finger-bar 1^x and outer levers 2' the bar 17 may be depressed without moving any of the printing-levers 2, so as reciprocate the spacing-bar 12 and traverse the table-frame 8 8', carrying 20 the paper to the extent of any desired space between words or letters without printing. A spring 14' is fitted on the spindle 14 to bring the ratchet rack-bar 12 always back to its outmost normal position (shown in 25 Figs. 3 and 6) and the transverse bar 17 up against the finger-levers 2. The traversing frame 8 also carries a small horizontal frame A, oscillating vertically on the swiveling bar 9 over the ratchet-rack 12, which carries the 30 vertical duplex pawl-frame B, with moving ratchet spring-pawl b, exactly over the teeth of the ratchet-rack 12. The frame B oscillates slightly on the pin B', and the spring-pawl b oscillates on the pin B'' at the upper part of 35 this oscillating frame B.

In the usual working of this machine the single depression of the finger-buttons 2' of the levers 2 while printing their ordinary alphabetical letter 6 on and by the lever 5 45 would only oscillate the rack 12 through the said bar 17 and levers 15 and 13 laterally to the extent of its own width—that is, so that the teeth of the ratchet-rack 12, while being moved forward, as described, by its lever 13, 50 clears the front edge of the spring-pawl b while printing the letter, and slips onto the second retaining ratchet-pawl b', fixed on the frame B, while the spring-pawl b moves forward by the strength of its spring b'', which 55 allows the frames A and 8 in the backward automatic traverse of the rack 12 to move forward to the extent of one tooth only, the spring-pawl b giving way to that extent before coming back against the frame B or a 60 stop b⁴ on it for the purpose.

By my improvements I make a few of the levers 5, as seen at 5^x 6^x in Figs. 1 and 2, to have a double set of two small letters at 6^x on them to print in the longitudinal direction; 65 or it might be three or more letters, as indicated in Fig. 4, instead of the single small and large alphabetical letters 6 at present mounted

on them and mounted round the greater part of the circle on the other levers 5, which print the alphabet in single letters. Fig. 4 shows a 70 face and edge view of one of these levers 5 with the letters "the" and "for" on it in small case or Roman type; and, further, in making the finger or key levers and knobs 2 and 2' at K, which move the printing-levers 75 5^x, as shown, to the right hand on the front of the key-board 1^x 1^x in Fig. 2, marked "th," "is," "it," "er;" or it may be three letters, as marked "the" or "for," to print these parts of words or complete small words which are 80 repeated frequently in correspondence; and I make these double or treble key-levers 2 2' to have a greater downward motion than single keys, which work the ordinary single-letter-printing levers, so that this extra motion will 85 depress another stepped knee-armed lever L L', mounted to the one side of the lower frame 1 under these key-levers 2, (indicated by these double or triple lettered words,) and through another extra link l will move one of the levers 15 and oscillate the spindle 14 and levers 13 to pull forward the spacing toothed rack 12 to two, three, or more times its own width, as dotted in in Fig. 6, and so allow the spring-pawl b b'' to move forward two, three, or more 90 teeth, according to the number of letters on the particular printing key-lever brought into action. Fig. 5 shows a side elevation of one new arrangement of the pawl mechanism for effecting this, to a large scale, with part of the 95 spacing toothed rack 12, and Fig. 6 a corresponding front view showing the rack as dotted in in its three positions on its lever 13 for either giving one, two, or three steps forward, according to the number of letters on the levers 2 2' printing for the time being, while 100 Figs. 7 and 8 show detail views of the new 105 spring-pawl b and spring stud-lever a a', detached from the views, Figs. 5 and 6. The said extra single or double lateral motion of 110 the rack 12 is made to oscillate a small spring stud-lever a a', fulcrumed at a'' on the upper part of the plate-frame B between this plate and the moving spring-pawl b and the back 115 fixed pawl b', so that the rack in being drawn forward acts on the lower end a² of the spring 120 stud-lever a a' against the power of the light spring a³ to shift the stud a', carried on it within segmental slots b'' b² b³, formed in the lower part of the spring-pawl b. These segmental slots are of three different sizes a very little larger than the three steps of the stem of the stud a' corresponding to them, as seen 125 particularly in Figs. 7 and 8, which allows the spring-pawl b to spring out to the extent of one, two, or three teeth, according to the position of the stud a' and as shown dotted in in Fig. 5, this stud in its normal position being always in the first slot b'' for giving one tooth or step forward of the frames B, A, and 8 carrying the paper after printing any of the one-letter-printing levers 5 and finger-keys 2 2'. 130

For printing any of the words or parts of words with two letters and their correspond-

ing printing-levers at 5×6^x and finger-keys at K, Fig. 2, marked with these letters the stud a' would be shifted by its lever a and the rack 12 to the second segmental slot b^2 in 5 the pawl-lever b and allow this to shift to the extent of two teeth or divisions, and when printing the words with three letters, as "the" or "for," then the stud a' would be shifted by its levers a and rack 12 to the wide slot b^3 of the 10 spring-pawl lever b to allow this to move forward to the extent of three teeth or divisions of the rack 12, and thus in either case on the rack 12 resuming its normal position the spring-pawl lever b would be forced back to 15 its normal position against the stud b^4 in the plate B, and the traversing frames A and 8 would traverse forward the paper to the extent of two or three teeth, respectively, as explained, to give the proper spacing to suit the 20 writing of two letters or words with three or more letters at a time, as described, by these improvements by the ordinary power of the coiled spring in the segmental wheel 11', all as for the one tooth and letter only heretofore 25 used.

In the working of this instrument the usual small single letters 6 on the levers 5 are printed by their respective keys 2 2' on the paper and roller 7, while the case 8', carrying the 30 journals of the paper-roller 7, is in its normal position close up toward the front of the frame 8, and kept there by the power of the usual spring S and levers S' and bar S², while for printing the capitals or large letters the case 35 A is moved back by a special key and lever marked "Upper Case," (seen to the left of the key-board in Fig. 2,) and an adjusting link and rod s, (shown in Fig. 3,) which actuates the levers s' and S' to push back the case 8' on 40 the rollers 8" of the frame 8, and thus print the capitals under the center of the roller 7. In like manner either set of the first or second new double or triple small letters 6^x on the levers 5^x, indicated more particularly in 45 Figs. 1 and 4, and actuated by the keys and finger-knobs indicated at K in Fig. 2, marked on the several finger-knobs "er" or "th," "an" or "in," "at" or "is," "to" or "of," and "the" or "for" are brought into action—that is, the 50 first double or triple letters "er" or "the" respectively of the several keys K are brought into action while the case 8' is in its normal forward position, while the second sets of double and triple letters "th" and "for" are 55 brought into action while the upper frame 8' is removed back by its key and finger-knob marked "Upper Case."

Another improvement consists in mounting a cam-bracket D, secured to the top 1' of the 60 fixed frame of the machine in front, and in such a position that as the paper-carriage is drawn back to the starting end of the machine before commencing a new line of printing it would automatically oscillate or raise 65 the ratchet hand-lever E E' and its pawls e to turn the ratchet-wheel F of the paper barrel 7 for taking up one, two, three, or more

teeth of this ratchet-wheel F at a time. This would turn the paper-roller 7 and give the different spaces or distances between the lines 70 of type-printing, either by pulling down the hand-lever E or by pushing it up, according as a pulling or pushing ratchet was employed, that shown being an ordinary construction of pushing ratchet-lever E e, which acts by 75 the lever E being raised up and has a downward-projecting limb E' for acting on the cam D as the carriage 8 with the paper is pushed back to raise the lever E and turn the ratchet-wheel F and roller 7 and paper 80 just before commencing a new line of type-writing. The lever E E' in this instance and the ratchet-wheel F, which it actuates, is for these improvements preferably mounted at the left-hand end of the reciprocating frame 85 8, instead of at the right-hand end, where it is usually placed for being actuated by the right hand of the attendant.

To hold down the front edge of the frame 8, while the lever E is being pressed up by 90 the cam D to turn the ratchet-wheel F, as described, a small catch-plate d is screwed to the under front edge and end frame 8, which, when this frame is pressed back, comes under another plate d', secured on the inner side of 95 the front rail 10. This plate d' is only long enough to hold down the frame 8 while the cam D is pressing up the lever E, but does not prevent the case 8' from being pushed backward on the frame 8 by the bar S², and 100 oscillated upon the swiveling bar 9 to see how the type 6 are printing on the under side of the paper when the lever E is no longer being acted on by the cam. The cam D may be adjusted to different positions for the different extents of movement to be given to the roller 7, and may be held in adjustment by means of its securing-screw D', Figs. 1^A and 3^A. I push or draw the carriage 8, with its paper and roller 7, by hand back to its 110 normal starting position, and in coming back this motion would automatically by the before-mentioned cam-bracket D and ratchet pawl-lever E E' turn the paper-roller 7 one, two, three, or more spaces, according to the 115 distance desired between the lines of printing for starting a new line.

It will be obvious that the same advance or feed motion of the carriage to the extent of one, two, or more teeth may be obtained 120 with the same mechanism when the pawls b b' are arranged to be moved across the ratchet-bar instead of having the ratchet-bar moved across the pawls. The ratchet-bar instead of the pawls may also be carried by the traversing carriage. Such a construction is shown, 125 for instance, in Figs. 5^A and 6^A, views corresponding in character with Figs. 5 and 6. The oscillating plate B B', in this modification carrying the moving pawl b and fixed 130 pawl b', is mounted on a frame or bar A', secured on the upper end of the same laterally-moving arms 13, to which in the construction already described the ratchet-bar 12 was se-

cured. The ratchet-bar 12 in this case is attached to a bar 8" on the oscillating part A of the carriage 8. The remaining parts are the same as already described and the operation is similar to that already explained. In both cases the relative movements of the pawls and rack and the varying extent of the movement are controlled by all the different keys for the different type.

10 I claim as my invention—

1. In type-writing or printing machines, the combination of the ordinary single type-levers with levers each carrying two or more types, ratchet-bar 12, movable and fixed pawls b b', one carrying an oscillating spring-lever which has a stepped stud and bears against the rack and the other having a stepped slot and key-levers controlling the type-levers, and means whereby the different 15 key-levers may impart different movements to the ratchet-bar and pawls relatively to each other, substantially as described.

2. In type-writing or printing machines, the herein-described combination of mechanism for printing two or more letters at a time from the type-levers, consisting of special 25 keys K, types 6^x, and type-levers 5^x, in combination with a differential pawl b, a laterally-moving ratchet-bar 12, a lever carrying 30 a stepped stud and acted on by the said bar

and levers to move the ratchet across the pawls to different extents according to the type-levers acted upon, substantially as set forth.

3. In type-writing or printing machines, the herein-described combination of mechanism for printing two or more letters at a time from the type-levers, consisting of key-levers K, ratchet-bar 12, oscillating lever a, having a stepped stud a', fixed pawl b, and 40 movable pawl b', having a stepped slot and levers to move the ratchet-bar across the pawl to different extents, substantially as set forth.

4. In type-writing or printing machines, the herein-described combination of mechanism 45 for regulating the spaces between the lines of print, consisting of a cam-bracket D, ratchet-lever E E', pawl e, pivoted frame, ratchet-wheel F, and roller 7, and a short plate to hold down the frame while the cam 50 is acting on the said lever.

In testimony whereof I have signed my name to this specification in the presence of two subscribing witnesses.

JOSEPH HUTCHISON.
